UNITED STATES PATENT OFFICE.

SAMUEL W. BICKLEY, OF MEXICO, MISSOURI.

SELF OPENING AND CLOSING HATCH-DOOR OF ELEVATOR-SHAFTS.

SPECIFICATION forming part of Letters Patent No. 288,612, dated November 20, 1883.

Application filed March 6, 1883. (No model.)

To all whom it may concern:

Be it known that I, SAMUEL W. BICKLEY, a citizen of the United States of America, residing at Mexico, in the county of Audrain and 5 State of Missouri, have invented certain new and useful Improvements in Self Opening and Closing Hatch-Doors of Elevator-Shafts, of which the following is a specification, reference being had therein to the accompanying 10 drawings.

My invention relates to certain improvements in elevators, and means for automatically closing and opening the shaft through which the car moves.

15 It consists, mainly, of an elevator-car provided on one of its faces with an upright plate provided with a vertical cam-groove, which terminates at its lower and upper ends with oblique grooves, which, as the car is raised or lowered, engages with a lever-arm connected with and working with other levers, one of which is slotted to give a horizontal movement to close and open a sliding hatch-door at every story.

25 In my drawings, Figure 1 is a plan view of an elevator-shaft, showing the sliding door, elevator-car, &c. Fig. 2 is an elevation, showing the timbers of said shaft and the car with its cam-groove, &c. Fig. 3 is a detail view in 30 elevation, showing an auxiliary closing device for the housing-groove of the cam-grooved plate.

Similar reference-letters denote like parts in all of the figures.

35 Referring to the drawings, A is the elevator-car, provided on one of its faces with a plate, B, which has a cam-groove, C, formed in a vertical line a greater portion of its length, and which terminates at its ends by an oblique 40 movement as it runs out of said plate. This plate B is rigidly fixed to the car, and extends its ends above and below the same.

45 On one side of the shaft, and extending the entire height of same, is fixed a grooved column, D, which serves as a housing and guide to the cam-plate, and also has a tendency to steady the movement of the car as it moves up and down in the shaft.

50 E is the hatch or door, arranged to slide on ways fixed against the joist of the floor between the flooring and ceiling, and when prop-

erly placed is intended to be concealed from view. To facilitate the easy movement of this hatch-door, I may form the bearings of metal, or provide anti-friction rollers or wheels, either 55 on said hatch or as substitute for the ways mentioned. At a point, a, in said hatch-door I provide a pin or pivot, a', provided with anti-friction roller, intended to take into the slotted end of a lever, F, pivoted at a', and connected by a pivot with an arm, G, which is in turn pivoted to one arm of a bell-crank lever, H, which has its fulcrum at a point, b. To the opposite arm of this bell-crank lever is pivoted an arm, I, which extends toward the cam-plate 65 B, and by its bent end reaches normally the line of movement of the openings of the cam-groove C.

The operation of my hatch-door-closing device may be described as follows: As previously stated, the free end of the compound lever connected with the said hatch-door is in normal position with hatch-door closed—*i. e.*, when in line with the upper or lower entrances of the cam-groove C. As the car is lowered 70 the walls of the groove C, impinging upon the side of the bent end of the lever I, forces said lever laterally against the bell-crank lever H, which moves the arm G, which in turn moves the lever-arm F, which latter arm, engaging 75 pin a by its slotted end, carries the hatch-door out to open the way for the downward-moving car. When the plate B reaches the line of the floor below, its groove in like manner engages a lever corresponding to that of I, and a second 80 door is opened and held open until the upper oblique portion of the groove C forces the said lever-arm back to the normal position, causing a reverse movement to the other lever-arms 85 associated with it, to close the hatchway. 90

It will be observed that when the projecting cam-plate attached to the side of the car is entirely above or below either floor-line, a small opening would be found at said line, which should be closed simultaneously with the hatch-door, in order to provide fully against draft-passages; and for this purpose I have arranged in connection with the cam-plate an auxiliary gate, K, a description of which is as follows: This gate I secure to a vertical rod, d, provided at its ends with short bent arms e f. The rod d, I hinge at points g h to the body of 100

the column D, and to the latter, also, I secure a spring, *i*, the free end of which bears against the gate K, to keep it normally closed. One of the vertical edges, as at *k*, of the cam-plate is spirally beveled at the top and bottom, so that when in the upward or downward movement of the car said beveled edges come in contact with the arms *e* or *f*, the rod *d* is revolved ninety degrees, and carries with it the gate K out of the way of the passage of the said cam-plate, said gate returning thereafter, by force of the spring, to close the opening in the said column. The end of the lever-arm *I* is to be provided with an anti-friction roller, to prevent wear of the groove and modify friction at that point.

In the construction of the frame-work in the vicinity of the elevator-shaft to which my devices are to apply, due regard must be had to providing at each floor of the building for one of these horizontally-sliding hatch-doors, as it is my intention to open and close the hatch-way at each story through the agency of my cam-plate and the levers associated therewith immediately after the top and bottom of the elevator-car passes the floor-line in its upward and downward movements, so that complete and effective barriers will be formed to prevent any draft movement from following in the wake of the said car, so that in case of fire the elevator-shaft, instead of serving to facilitate the spread of the flames, will form a damper, to check the same. I do not wish to confine myself to this precise arrangement of le-

vers or to their direct or indirect connection with the hatch-door.

I am aware that hinged hatch-doors have been closed automatically through the engagement of a groove in the cab or car with the arms of levers pivoted to a lazy-tongs arrangement, and to such I make no claim; but

What I do claim, and desire to secure by Letters Patent, is—

1. The combination, with the car of an elevator, of the plate B, provided with a vertical groove having oblique termini at its opposite ends, adapted, in the upward and downward movement of said car, to engage a lever-arm to act upon associated lever-arms to open and close a horizontally-sliding hatch-door, substantially as set forth.

2. The elevator-car provided with a vertical cam-groove, C, having oblique termini at its opposite ends, in combination with the levers described and a sliding hatch-door, substantially as specified.

3. In combination with the grooved plate B, beveled, as described, the gate K, rod *d*, and spring *i*, as and for the purpose herein set forth.

In testimony whereof I affix my signature, in presence of two witnesses, this 28th day of February, 1883.

SAMUEL W. BICKLEY.
